UNITED STATES PATENT OFFICE.

BENEDICT F. VOGT, OF LOUISVILLE, KENTUCKY.

HANDLE FOR BOTTLES AND LIKE CONTAINERS.

No. 896,673.

Specification of Letters Patent.

Patented Aug. 18, 1908.

Application filed June 1, 1908. Serial No. 435,979.

To all whom it may concern:

Be it known that I, BENEDICT F. VOGT, a citizen of the United States, residing at Louisville, in the county of Jefferson and State of Kentucky, have invented certain new and useful Improvements in Handles for Bottles and Like Containers, of which the following is a specification.

My present invention pertains to improvements in handles for bottles and like containers, the construction and advantages of which will be hereinafter set forth, reference being had to the annexed drawings, wherein:

Figure 1 is a perspective view of the handle; Fig. 2 a sectional elevation of the handle and a portion of the bottle, showing the handle in position upon the bottle; and Fig. 3 a side elevation of the upper portion of the bottle, the handle being broken away.

20 The object of the invention is to provide a simple and efficient handle for bottles, one which may be readily attached to the bottle and removed therefrom if necessary, the construction being such that the device may be 25 readily secured in place without the use of tools.

With the construction, which will be hereinafter set forth in detail, a relatively wide handle and bail therefor may be employed, 30 thereby affording a ready grip for the hand. The construction also permits the handle to be swung downward to one side of the bottle, which swinging movement may be utilized when it is desired to pour out the contents of 35 the bottle.

Referring to the drawings, 1 denotes the neck of the bottle or like container, having the usual outwardly-projecting rim or collar 2 formed at the upper end thereof. The handle proper is designated by 3, and is mounted upon a bail 4, the arms of which stand in substantial parallelism and are provided with eyes 5 at their lower ends. These eyes pass into similar eyes 6 formed upon the outer 45 ends of a supporting bar 7 which, as will be seen upon reference to Fig. 1, is provided with a semicircular or outwardly-curved section 8 adapted, when the parts are in position, to lie close against the neck of the bottle, 50 beneath the rim or collar 2.

A latch or retaining member 9, complementary in form to section 8, is secured by an eye 10 to the cross or supporting bar, the opposite end of the latch being provided with a hook or finger 11 which, when the parts are 55 in position, passes over and embraces the sup-

porting bar 7 adjacent to the junction of the curved portion 8 with the body of the bar.

The parts will preferably be formed of wire which has sufficient temper and strength 60 to prevent the same from readily bending, but the hook 11 of the latch member 9 may be readily swung over the bar 7 when the parts are to be positioned. The latch will retain this position unless forcibly displaced. 65

As will be seen upon reference to Figs. 2 and 3, the finger or hook 11 will be held close against the bottle-neck when the bottle is raised by the handle, and thus displacement of the hook is absolutely prevented. 70

By making the bar 7 extend outwardly from the bottle-neck, the handle 3 may be of such length as to permit it to be readily grasped by the hand.

It is conceivable, of course, that after the 75 latch 11 has been passed over and brought into engagement with the supporting bar 7, it might be closed upon itself and upon said bar by pincers or any other suitable device.

When the parts are to be positioned upon 80 the bottle, they will preferably assume the locations shown in dotted lines in Fig. 3, with the embracing section 8 of the cross bar lowered and the latch member 9 thrown into such position that the latch hook 11 may be 85 readily passed over the supporting bar.

The construction also permits the rotation of the bottle with reference to the handle, which is a point of advantage if the bottle-mouth should become chipped or broken, or 90 be formed with a lip from which the contents of the bottle may be poured.

Having thus described my invention, what I claim is:

1. In a handle for bottles and like containers, the combination of a cross bar provided at its center with a semicircular section adapted to lie against the neck of the bottle; a latch wire of semicircular outline secured at one end to the cross bar and provided with a hook at its opposite end, adapted to engage the cross bar; and a handle secured to the cross bar. 95 100

2. In a handle for bottles and like containers, the combination of a supporting bar provided with a semicircular section adapted to lie against one portion of the bottle-neck; a retaining wire semicircular in outline adapted to bear against the opposite portion of the bottle-neck and adapted to be secured 105 at its ends to the supporting bar; and a bail secured to the outer ends of said bar. 110

3. In a handle for bottles and like containers, the combination of a cross or supporting bar provided at its center with an outwardly-curved, substantially semicircular section; a latch wire pivoted to the bar adjacent to one end of said curved section and provided with a retaining latch or finger adapted to embrace the bar adjacent to the junction of the curved section with the opposite end of the bar; and a bail pivotally secured to the outer ends of the bar.

4. In a handle for bottles and like containers, the combination of a cross or supporting bar provided with a section substantially semicircular in form to embrace the neck of the bottle, the ends of the bar extending outwardly therefrom and being

provided with eyes; a latch wire substantially semicircular in form, said wire being pivotally secured at one end to the cross bar; 20 a hook or finger formed upon the opposite end of the latch wire and adapted to embrace the cross bar when the parts are in position; a bail pivotally secured to the eyes formed upon the cross bar; and a handle-piece carried by the bail.

In testimony whereof I have signed my name to this specification in the presence of two subscribing witnesses.

BENEDICT F. VOGT.
